Fig 4

Fig 5

Fig 6

Fig 7

Fig 8

Fig 9

FIG. 1 is a top plan view of a tape recorder or similar article showing my new design with the cover raised;

FIG. 2 is a perspective view thereof;

FIG. 3 is a perspective view of a design for a tape recorder or similar article showing my new design with the cover closed;

FIG. 4 is a front elevational view thereof;

FIG. 5 is a right-hand elevational view thereof;

FIG. 6 is a rear elevational view thereof;

FIG. 7 is a left-hand elevational view thereof;

FIG. 8 is a top plan view thereof; and

FIG. 9 is a bottom plan view thereof.

I claim:

The ornamental design for a tape recorder or similar article, substantially as shown and described.
